UNITED STATES PATENT OFFICE.

JOHNATHAN R. FREEZE, OF MIDDLETOWN, OHIO, ASSIGNOR, BY MESNE ASSIGNMENTS,
TO THE AMERICAN ROLLING MILL COMPANY, OF MIDDLETOWN, OHIO, A CORPORA-
TION OF OHIO.

SILO-DOOR.

1,243,829.

Specification of Letters Patent. Patented Oct. 23, 1917.

Application filed November 21, 1916. Serial No. 182,695.

To all whom it may concern:

Be it known that I, JOHNATHAN R. FREEZE, a citizen of the United States, residing at Middletown, Butler county, Ohio, have invented certain new and useful Improvements in Silo-Doors, of which the following is a specification.

This improvement pertains to silo doors and, while it is suitable for a variety of structures of various forms it has been devised with special reference to the shells of silos circular in plan, and the invention is so illustrated.

The invention will be readily understood from the following description taken in connection with the accompanying drawings in which:—

Figure 1 is a front elevation of a silo door exemplifying my invention, the door being shown partly open:

Fig. 2 a horizontal section of the same in the plane of line *a* of Figs. 1 and 3:

Fig. 3 a vertical section in the plane of line *b* of Figs. 1 and 2:

Fig. 4 a similar vertical section of portions of the structure in the plane of line *b* of Figs. 1 and 2: and

Fig. 5 a horizontal section of portions of the structure in the plane of line *c* of Fig. 1.

A diversity of scales is employed in the drawings.

In the drawings:—

1, illustrates a portion of the shell of a sheet metal silo of circular plan:

2, the door-opening therein, illustrated as being rectangular:

3, horizontal bars of Z-shaped cross-section riveted to the shell, one bar at the upper margin and one at the lower margin of the door-opening, these bars forming grooves at the top and bottom of the door-opening, one groove opening downwardly and the other groove opening upwardly, the width of the grooves tapering from one end of the doorway to the other:

4, Z-shaped bars riveted to the shell and forming prolongations at the wide ends of the grooves which have been referred to:

5, a Z-shaped bar riveted to the shell at that margin of the door-opening corresponding with the narrow ends of the grooves formed by the bars 3, this vertical Z-bar forming a vertical groove at the end of the door-opening:

6, a notch cut in the inwardly projecting flange of the Z-bar 5:

7, the door, which is formed of sheet metal of a size to cover the door-opening and extend vertically from the floor of the bottom groove to the roof of the top groove, this door being curved to fit against the outer surface of the shell at the margins of the door-opening:

8, an outwardly projecting roll formed by curling that one of the vertical edges of the door corresponding with the wide ends of the horizontal grooves in which the door slides:

9, a similar roll formed at the opposite side edge of the door:

10, ladder-rounds riveted to the outer face of the door: and

11, channel-bars, with their channels facing outwardly, riveted to the outer surface of the door at its upper and lower edges, these bars being tapered to correspond with the taper of the grooves formed by the bars 3, and of such dimensions that when the door is slid shut they fill the grooves at the top and bottom of the doorway.

Assume the door to be slid fully open and to be supported by the grooves in bars 4. The bars 4 thus prevent the falling away of the door, and if there is no objection to the door becoming separated from the shell when the door is open then the bars 4 need not be provided.

When the door is pushed to the left to the fully closed position, the channel-bars have a wedging fit in the upper and lower grooves and cause the door to be tightly pressed against the shell.

The rolls 8 and 9 stiffen the vertical edges of the door and the vertical Z-bar 5 stiffens one of the vertical margins of the doorway, and, when the door is pushed to closed position, roll 9 becomes housed within vertical Z-bar 5 and pressed to the shell.

It is preferred that the door fit rather tightly in the top and bottom grooves when the door is in closed position, and the door may be started open by a driving operation, but the notch 6 in the vertical Z-bar permits of the use of a pinch-bar in starting the door open.

In silos it is highly desirable to avoid interior projections and in the present case projections are avoided by countersinks at

the inner ends of the rivets holding parts to the shell, and countersinks at the inner ends of the rivets, securing the channel-bars to the door and securing the ladder-rounds to the door, permit the door to slide freely on the outer surface of the shell.

I claim:—

1. In a door, the combination of a shell provided with a rectangular door-opening, 10 horizontal bars secured to the shell in front of the upper and lower margins of the door-opening, and forming walls closer to the shell at one end than at the other whereby the upper and lower margins of the door-opening become provided with tapering grooves 15 facing toward each other, a door adapted to close the opening and having its horizontal edges slideable in said grooves, and tapering members provided at the horizontal margins 20 of the door and adapted to tightly fill said grooves when the door is pushed to closed position, substantially as set forth.
2. A structure as specified in claim 1 when the grooves are formed of tapering 25 Z-shaped bars secured to the shell at the horizontal margins of the door-opening, substantially as set forth.
3. A structure as specified in claim 2 in combination with Z-shaped bars secured to 30 the shell and forming endwise prolongations of the grooves at their wider ends beyond

the side margin of the door-opening, substantially as set forth.

4. A structure as specified in claim 1 in combination with a roll formed at each vertical edge of the door and having its ends 35 engaging said grooves, substantially as set forth.

5. A structure as specified in claim 1 when the tapering members at the horizontal margins of the door are formed of tapering channel-bars secured to the exterior surface 40 of the door, substantially as set forth.

6. A structure as specified in claim 1 in combination with a vertical member carried 45 by the shell at the closing margin of the door and forming an inwardly open groove, and a roll formed on the closing vertical edge of the door and having its ends engage 50 said horizontal grooves and adapted to enter the vertical groove, substantially as set forth.

7. A structure as specified in claim 6 when the outer wall of said vertical groove is notched to permit access of a tool to the roll 55 when the door is closed, substantially as set forth.

JOHNATHAN R. FREEZE.
